BOTTLE STERILIZER

Earl G. Thompson, San Francisco, Calif.

Application July 10, 1948, Serial No. 38,042

3 Claims. (Cl. 21—79)

1

My invention relates to a bottle sterilizer. More particularly, my invention relates to a collapsible bottle sterilizer which is particularly useful for sterilizing baby bottles. It is to be expressly understood that my invention is not limited to a sterilizer for baby bottles and that the same is set forth by way of illustration and not by way of limitation.

At times, it is necessary to travel with a nursing baby and the problem then arises as to how the baby bottles can be sterilized. Also, around one's home, a compact and collapsible bottle sterilizer is desired. It is an object of my invention to provide a bottle sterilizer which meets the needs above described.

It is a further object of my invention to provide a bottle sterilizer which employs a minimum amount of water and hence a maximum utilization of the heat employed to provide the sterilizing heated water vapor or low pressure steam.

It is a further object of my invention to provide a bottle sterilizer which is capable of sterilizing bottles standing on end with the open end portion downwardly and which sterilizer can be employed to sterilize either the small mouth type baby bottles or the large mouth type baby bottles.

It is a further object of my invention to provide a device which functions not only as a bottle sterilizer, but also which may be utilized as a bottle carrying rack or storage rack for baby bottles, filled or empty.

It is a further object of my invention to provide devices which are simple in construction, capable of mass production, sturdy and reliable.

The above mentioned general objects of my invention, together with others inherent in the same, are attained by the devices illustrated in the accompanying drawings throughout which like reference numerals indicate like parts:

Figure 1 is a perspective view of a device embodying my invention;

Fig. 2 is a transverse sectional view, with parts in end elevation of the same, the handle being also shown by dotted lines to indicate its pivotal connection;

Fig. 3 is a fragmentary view in side elevation, on a smaller scale, and taken substantially at right angles to Fig. 2; and

Fig. 4 is a fragmentary detached sectional view with parts in elevation of a portion of the rack means shown in the preceding figures.

Referring now to the construction shown in Figs. 1 to 4 of the drawings, a tray means comprises the tray 7 and a cover 8 therefor. The

2

cover 8 is removable and rests on a shelf 9 in the upper edge portion of the tray 7. The shelf 9 is best shown in Fig. 2 of the drawings. The cover 8 is provided with a plurality of sets of depressions 10 and 11, each set of which is concentric with an opening 12 (see also Fig. 2 of the drawings). The depression 10 is of a size to snugly fit and receive therein the opening of a standard wide mouth baby bottle, and the depression 10 is of a size to snugly fit and receive therein a standard small mouth baby bottle. The opening 12 functions as an exhaust port for water vapor or low pressure steam created by heating water disposed in the tray 7.

15 Flat straps 13 are preferably made of spring steel and thus form leaf spring means. Intermediate their length, the straps 13 are pivotally connected to the tray 7 as by pivot means 14.

A rack for holding the upper portion of vertically disposed bottles comprises a rim portion 15 and rods 16. The rods 16 function to provide a plurality of individual compartments to support bottles, such as six compartments. The rim section 15 may be made up of two members which 20 are identical in construction and which are U-shaped members. Then the U-shaped members are mated and may be held in place by crimping end members 17 thereover. The end members 17 are provided with openings 18 (see also Fig. 4) to receive tines 19 carried by the straps 13. The longitudinal rod 16 is carried by end members 17 and the transverse rods are carried by rim portions 15. This may be accomplished by having reduced end portions on the rods 25 interfitting with openings in the members 17 and 15 as shown.

As best shown in Fig. 3 of the drawings, straps 13 are movable from a down or full line position shown in Fig. 3 to the up or dotted line position 40 shown. When in the dotted line position, the lower portion of each strap 13 will engage the tray 7 before the strap 13 assumes a vertical position. Thus when the rack comprising members 15—16—17 is disposed between two flat straps 13, 45 there will be a resilient pressure urging strap 13 towards said rack.

Handle or bail 20 is pivotally connected by pivot means 21 at its respective end portions to the end members 17. Washer means 22 (see Fig. 1) space each end portion of handle or bail 20 from the end members 17. The spacing provided by the washer means 22 is such that a strap 13 may have a portion between a lower end portion of the handle 20 and an end member 17.

Assuming that the device is collapsed, then the

handle is turned so that its leg portions are parallel to the rack 15—16—17. Then one strap 13 is moved from the full line position shown in Fig. 3 to the dotted line position shown in Fig. 3 and the tines 19 of the strap 13 are inserted in openings 18 in an end member 17. Next, the strap 13 at the opposite end of the device is moved from the full line position shown in Fig. 3 to the dotted line position and its tines 19 are inserted in the other openings 18 at the opposite end of the rack 15—16—17. There will be sufficient spring pressure, because of the nature of straps 13, to tend to hold the parts in the position indicated. As a lock to hold such parts in position, the handle 20 is turned 90° and the lower end portions will overlay a portion of the straps 13 and thus a positive lock is provided preventing accidental collapsing of the structure.

The cover 8 is readily movable and is preferably removed to insert water in the tray 7. Then bottles of either the large mouth style or the small mouth style are inserted with the mouth down over the openings 12 and interfitting with depressions 10 or 11 depending on the style of the bottle. As heat is applied, water vapor or low pressure steam arises out opening 12 and gradually replaces the air in the bottle and sterilizes the inside of the baby bottle. Very little water need be placed in the tray 7 as little water vapor or low pressure steam is lost during the sterilizing process.

From the foregoing description of devices illustrating my invention, it is obvious that I have provided a baby bottle sterilizer which comprises a tray member 7 and a cover 8, said cover 8 having spaced openings in the upper surface thereof through which heated water vapor or low pressure steam may pass and over which openings may be positioned, the open portions of bottles to be sterilized. The tray member 7 and cover member 8 thus function as a generator means for heated water vapor or low pressure steam and are so designated in the claims. Also, I have provided spaced rack means to said tray member and means to collapsibly interconnect said tray means and said rack means. Furthermore, I have provided depressions in the cover of the tray so that the depressions will interfit with standard small mouth bottles as well as standard wide mouth baby bottles. In Figs. 1 to 4 I have indicated straps 13 which are pivoted to the tray and detachably connected with the rack as a means to collapsibly interconnect the tray and the rack. These general features of my invention together with more specific features are set forth in the foregoing specification and in the annexed claims.

Obviously, changes may be made in the forms, dimensions, and arrangement of the parts of my device, without departing from the principle thereof.

I claim:

1. In a bottle sterilizer, a generator means for heated water vapor comprising a liquid container tray means and a cover means therefor, said cover means having openings in the upper surface portion thereof to provide therethrough a source of heated water vapor and to receive over said openings the open end portions of bottles to be sterilized; bottle supporting rack means disposed in vertical spaced relation to said generator means and providing a support for the closed end portions of vertically disposed bottles having their open end portions disposed over said openings in said cover means, said rack

means having fine receiving openings in opposite edge portions thereof; connecting strap means between said tray means and said rack means comprising diametrically disposed spaced apart strap means each hingedly secured to said tray means intermediate its length on hinges parallel to an edge of said tray means, abutting at the lower end portion said tray means, and terminating in a plurality of tines interfitting in the said openings in an edge portion of said rack means; and handle bail means pivoted to said rack means intermediate the length of each leg thereof and having the lower end of each leg movable into and out of outside surface contacting relation with the upper portion of one of said strap means and securing the tines of said strap means in the openings of said rack means.

2. In a bottle sterilizer, a generator means for heated water vapor comprising a liquid container tray means and a cover means therefor, said cover means having openings in the upper surface portion thereof to provide therethrough a source of heated water vapor and to receive over said openings the open end portions of bottles to be sterilized; bottle supporting rack means disposed in vertical spaced relation to said generator means and providing a support for the closed end portions of vertically disposed bottles having their open end portions disposed over said openings in said cover means of said tray means, said rack means having fine receiving openings in opposite edge portions thereof; connecting strap means between said tray means and said rack means comprising diametrically disposed spaced apart strap means each hingedly secured to said tray means intermediate its length on hinges parallel to an edge of said tray means, abutting at the lower end portion said tray means, and terminating at its upper portion in a plurality of tines interfitting in the said openings in an edge portion of said rack means; and spaced apart locking pawl means each pivoted to opposed portions of said rack means at the level of said upper portions of said strap means and each having a portion thereof movable into and out of outside surface contacting relation with the upper portion of one of said strap means and securing the tines of said strap means in the openings of said rack means.

3. In a bottle sterilizer, a generator means for heated water vapor comprising a liquid container tray means and a cover means therefor, said cover means having openings in the upper surface portion thereof to provide therethrough a source of heated water vapor and to receive over said openings the open end portions of bottles to be sterilized; bottle supporting rack means disposed in vertical spaced relation to said generator means and providing a support for the closed end portions of vertically disposed bottles having their open end portions disposed over said openings in said cover means, said rack means having fine receiving openings in opposite edge portions thereof; connecting flat spring strap means between said tray means and said rack means comprising diametrically disposed spaced apart strap means each hingedly secured to said tray means intermediate its length on hinges parallel to an edge of said tray means, abutting at the lower end portion said tray means, terminating in a plurality of tines interfitting in the said openings in an edge portion of said rack means and resiliently urged toward said rack means; and spaced apart locking means each carried by said rack

5

means and securing the tines of said strap means in the openings of said rack means.

EARL G. THOMPSON.
